CLAIM

The ornamental design for a universal utility rack, substantially as shown and described.

DESCRIPTION

FIG. 1 is a front, perspective view of a first embodiment of a universal utility rack;
FIG. 2 is a left-side view thereof, the right-side view being a mirror image thereof;
FIG. 3 is a front view thereof;
FIG. 4 is a rear view thereof;
FIG. 5 is a top view thereof;
FIG. 6 is a bottom view thereof;
FIG. 7 is a front, perspective view of a second embodiment of a universal utility rack;
FIG. 8 is a left-side view thereof, the right-side view being a mirror image thereof;
FIG. 9 is a front view thereof;
FIG. 10 is a rear view thereof;
FIG. 11 is a top view thereof;
FIG. 12 is a bottom view thereof;
FIG. 13 is a front, perspective view of a third embodiment of a universal utility rack;
FIG. 14 is a left-side view thereof, the right-side view being a mirror image thereof;
FIG. 15 is a front view thereof;
FIG. 16 is a rear view thereof;
FIG. 17 is a top view thereof;
FIG. 18 is a bottom view thereof;
FIG. 19 is a front, perspective view of a forth embodiment of a universal utility rack;
FIG. 20 is a left-side view thereof, the right-side view being a mirror image thereof;
FIG. 21 is a front view thereof;
